DRIVING MECHANISM

John E. Regan, Syracuse, N. Y., assignor to The Lamson Company, Syracuse, N. Y., a corporation of Massachusetts

Original application March 8, 1935, Serial No. 9,993. Divided and this application November 29, 1935, Serial No. 51,977

4 Claims. (Cl. 74—301)

This invention forming the subject matter of the present application (a division of my copending application Serial No. 9,993, filed March 8, 1935) relates to a driving mechanism including a source of power and a planetary reduction gear and to the structure and operation of such gear.

The objects of this invention include the following, to provide a driving mechanism which will automatically react to any overloading and will refrain from imparting driving impulse until the overload has been relieved; to provide as a part of such mechanism a planetary reduction gear by which the driving impulse relative to the speed of the source of power may be altered, such gear unit being so instructed that the moving elements thereof run in a lubricant, and including a driven shaft and gear elements rotatably supported by the driven shaft.

These and other objects will appear from an examination of the following specification and of the drawings which form a part thereof and in which:

Fig. 1 is a view in side elevation of a driving mechanism embodying this invention;

Fig. 2 is a plan view thereof;

Fig. 3 is a sectional view on an enlarged scale of the gear unit which forms a part of the driving mechanism shown in Figs. 1 and 2;

Fig. 4 is a sectional view taken along the line 30—4—4 of Fig. 3; and

Fig. 5 is a view in elevation of the spider which is one element of the gear unit.

The driving mechanism comprises a motor 22, a stepped pulley 23, a belt 24, a stepped pulley 25, a counter shaft 26, sprocket 27, chain 28, sprocket 29, and a gear reduction unit 30. The unit 30 includes a casing 31 on which is supported the yoke 32 which carries the shaft 26, on the ends of which are fixed the pulley 25 and sprocket 27. The motor 22 and unit 30 are supported upon a block or plate 33. The motor 22 rests on a bed 35 pivotally mounted upon the block 33 and is yieldably held by a tension device 36, which engages both the motor casing and the yoke 32, so that the belt 24 is taut regardless of which steps of the pulleys are engaged. The tension device 36 yieldably opposes any tendency of the motor bed 35 to rock forwardly toward the pulley and loosen the tautness of the belt.

Mounted at the center of the casing 31 is a main shaft 37 supported by the walls of the casing on bearings 38 and 39. One end of the shaft 37 projects beyond the casing 31 and on it may be fixed a gear or sprocket or other driving instrumentality. Keyed to the shaft 37 within the casing and adjacent the bearing 39 is a spider 40 (see Fig. 5). Projecting from the spider 40 are a plurality of studs 41 on which rotate freely a plurality of spur gears 42. A ring 43 receives the ends of the studs 41. Surround-

ing the shaft 31, and separated therefrom by plain bearings 44, is a floating gear assembly 45. This assembly comprises an inner U-shaped external ring gear 46 and an opposed outer U-shaped internal ring gear 47. The ring gear 46 is made up of two sections and is provided at the outer edges of its legs with annular rows of teeth forming the tracks 48 and 49. The legs of the gear 47 are also provided at the outer edges with annular rows of teeth forming the tracks 50 and 51 which encircle the tracks 48 and 49 respectively. The track 48 of the gear 46 has fewer teeth than the track 49, and is on a smaller circle, and the track 50 of the ring gear 46 bears a similar relation to the track 51. In addition the ring gear 47 floats relative to the ring gear 46 being provided with a central flange 52 terminating in a sleeve 53 which enters the space between the legs of the ring gear 46, and is separated therefrom by plain bearings 54. Spaced 20 openings 55 are formed in the flange 52 to reduce weight and to facilitate the flow of lubricating oil, as will be pointed out hereinbelow. The spur gears 42 of the spider 40 mesh at all times with the track 49 of the ring gear 46 and 25 with the track 51 of the ring gear 47.

Mounted upon the cover plate 56 of the casing 31 are a plurality of idler pinions 57 (four being here provided), which mesh with the track 48 of the ring gear 46 and with the track 50 of the ring gear 47 (see Fig. 4). The studs 58 of the pinions 57 are received at one end in a ring 59 which carries a bearing 60 to receive one end of a stud shaft 61 on the other end of which the sprocket 29 is mounted. The shaft 61 enters 35 the casing 31 through an opening 62 in the cover plate 56, the opening being closed by a cover 63 fastened to the plate 56 and provided with a bearing 64 for the shaft 61. Pinned to the shaft 61 is a gear 65 which meshes with a gear 66 rotatable about the shaft 37 upon plain bearings 67. The idler pinions 57 are of sufficient width to mesh simultaneously with the gear 66, the track 48 of the ring gear 46 and the track 50 of the ring gear 47, the teeth of the gear 66 and the track 48 being equal in size, number and dimension. The drive from the motor 22 to the sprocket 29 is transmitted through the gears 65 and 66 and the idler pinions 57 to the ring gear 46 and the ring gear 47 causing them to rotate 50 in the opposite directions. The ring gear 46 and ring gear 47 act simultaneously upon the spider gears 42 through the tracks 49 and 51 and rotate the spider in the well known manner, thereby causing the rotation of the shaft 37.

The gear reduction unit thus described is very compact and, with the exception of the sprocket 29, all the gear elements are completely enclosed within the casing 31. These enclosed elements run in oil or other lubricant introduced through 60

an inlet closed by a breather plug 68 and drained off through an outlet normally closed by a plug 69. The lubricant reaches the plain bearings 44 on the shaft 37 through a plurality of holes 70 formed in the sleeves 53 of the ring gear 47 and a plurality of holes 71 through the base of the reverse gear 46. The bearing 64 for the shaft 61 is lubricated through a hole 72 in the cover 63. The other bearings are, as shown in the drawings, so exposed that the lubricant flows freely thereto.

The spider 40 is keyed to the main shaft 37 and the speed and direction of travel thereof is determined by the relative ratio of the number of teeth in the ring gears 46 and 47. In the unit shown in the drawings the shaft 37 is rotated in a direction opposite to that of the shaft 26. In some other ratios the shaft 37 may be rotated in the same direction as the shaft 26.

20 The amount of reduction obtained by the use of a unit of this construction can be varied as desired. In the one illustrated a ratio of approximately 175 to 1 is obtained, the gear 65 having fourteen teeth, the gear 66 having twenty-eight teeth, each pinion 57 having fourteen teeth, the track 48 having twenty-eight teeth, the track 50 having fifty-six teeth, the track 49 having thirty teeth, the track 51 having fifty-eight teeth, and each spider gear 42 having fourteen teeth. 25 The desired amount of reduction may be selected without regard to the direction of travel given thereby to the shaft 37 since the motor may be reversed if necessary. However if a definite direction is desired it is possible to select a combination of gears to select a ratio which will give the desired direction of rotation.

In order to increase or decrease the speed of travel of the shaft 37 the tracks and gears shown may be replaced by other tracks and gears of different pitches, diameters, etc. It will be noted that, since all the revolving members are supported by or around the shaft 37, these changes can be made without disturbing the centers of the racks and gears. Hence complete assemblies of gear units having various ratios may be prepared and kept on hand for use in the housing whenever a change in the speed of the sprocket is desired.

In case the motor 22 should be overloaded, as for example, if any jam or blockage should take place in the driven mechanism, the supply of power thereto will be automatically cut off, the strain on the motor 22 increasing the tendency of the motor bed 35 to rock forwardly so that the tension device 36 will yield and the belt 24 be slackened, allowing the motor to run freely without driving the pulley 25.

I claim:

1. A gear reduction unit comprising a casing, a driven shaft supported centrally of the casing for rotation therein, a drive shaft supported by said casing parallel to said driven shaft, a gear fixed to said drive shaft, a gear rotatable about said driven shaft and in mesh with said first-mentioned gear, a plurality of pinions carried by said casing and in mesh with said rotatable gear, a floating gear assembly supported by said driven shaft and rotatable independently thereof by said pinions, and a spider keyed to said driven shaft and including a plurality of spur gears driven by said floating gear assembly whereby said drive shaft actuates said driven shaft.

2. A gear reduction unit comprising a casing, a driven shaft supported centrally of the casing for rotation therein, a drive shaft supported by said casing parallel to said driven shaft, a floating gear assembly supported by said driven shaft and rotatable independently thereof, said gear assembly consisting of an inner U-shaped ring gear having a pair of spaced external gear tracks and an outer U-shaped ring gear having a pair of spaced internal gear tracks in alignment with the tracks of the inner gear, a spider keyed to the driven shaft, and including a plurality of spur gears constantly in mesh with one of said internal gear tracks and the external gear track in alignment therewith, a plurality of idler pinions carried by said casing and constantly in mesh with the other of said internal gear tracks and the external gear track in alignment therewith and means carried by said drive shaft for rotating said pinions in unison and thereby through the gear assembly and spider rotating said driven shaft.

3. A gear reduction unit comprising a casing, a driven shaft supported centrally of the casing for rotation therein, a drive shaft supported by said casing parallel to said driven shaft, a floating gear assembly supported by said driven shaft and rotatable independently thereof, said gear assembly consisting of an inner U-shaped ring gear having a pair of spaced external gear tracks, and an outer U-shaped ring gear having a pair of spaced internal gear tracks in alignment with the tracks of the inner gear, a spider keyed to the driven shaft, and including a plurality of spur gears constantly in mesh with one of said internal gear tracks and the external gear track in alignment therewith, a plurality of idler pinions carried by said casing and constantly in mesh with the other of said internal gear tracks and the external gear track in alignment therewith, a gear rotatable about the driven shaft and constantly in mesh with said pinions and a gear carried by said drive shaft and in mesh with the gear rotatable about the driven shaft for rotating said pinions in unison and thereby through the gear assembly and spider rotating said driven shaft.

4. A gear reduction unit comprising a casing, a driven shaft supported centrally of the casing for rotation therein, a floating gear assembly supported by said shaft and rotatable independently thereof, said gear assembly consisting of an inner ring gear having a pair of spaced external gear tracks, one of said tracks being on a larger circle than the other of said tracks, and an outer ring gear having a pair of spaced internal gear tracks in alignment with the tracks of the inner ring gear which is on the larger circle being on a larger circle than the other track of the outer ring gear, a spider keyed to the driven shaft and including a plurality of spur gears constantly in mesh with the aligned tracks of the inner and outer ring gears on the larger circles, a plurality of idler pinions carried by the casing constantly in mesh with the other aligned tracks of the inner and outer ring gears, a drive shaft and means actuated by said drive shaft for rotating said pinions, and, through the gear assembly and spider rotating said driven shaft.

JOHN E. REGAN.
